ESCAPEMENT MECHANISM FOR TYPE-WRITERS AND THE LIKE

Seyed Khalil, New York, N. Y.

Application July 16, 1949, Serial No. 105,231

31 Claims. (Cl. 197—87)

1

This invention relates to improvements in rotary dog escapement mechanism for typewriters and the like, and is particularly directed to the provision of novel means which convert the reciprocating strokes of a universal bar into stepped rotary movement for rotating said rotary dog; and has for a primary object the provision of a converting mechanism which operates unerringly regardless of the speed at which a typist types.

The escapement mechanisms which operate with said rotary dog, are termed "unidirectional," while the prevailing escapement mechanisms (widely used today) in which a dog or a dog-rocker (carrying several dogs), moves back-and-forth, for each typing action, are termed "oscillatory" escapement mechanisms.

Despite their superiority over the oscillatory escapement mechanisms for producing more uniform impressions, said unidirectional escapement mechanisms are discarded in favor of said oscillatory escapement mechanism.

The main reason for abandoning said unidirectional escapement mechanism in favor of said oscillatory escapement mechanism, lies in the "speed limitation" of said unidirectional escapement mechanisms. They do not respond to the modern high speed typing.

Said speed limitation of said unidirectional escapement mechanisms is due to the portions of the mechanism employed to change the reciprocal motion of the universal bar into stepped rotary motion in one direction.

To change the reciprocal motion of the universal bar into rotary motion, said unidirectional escapement mechanisms employ a ratchet mechanism comprising a ratchet wheel secured to the rotary dog, a propelling pawl which is motivated by the universal bar for driving said ratchet wheel, and a retaining pawl for said ratchet.

Other defects of said unidirectional escapement mechanisms such as, for example, weakness of their parts which are due to "space limitation," will be described in the course of this specification.

My unidirectional escapement mechanism is, in many respects, and particularly in respect to its high speed of operation, superior to and novel as compared to all unidirectional escapement mechanisms of the prior art.

Having no "drop" movement, which is an inherent defect of said oscillatory dogs, and which is the cause of crowded impressions, my unidirectional escapement mechanism is also superior to said oscillatory escapement mechanism.

2

Unidirectional escapement mechanisms of the prior art

As far as I know, among several unidirectional escapement mechanisms of the prior art, a U. S. patent, No. 514,807, was issued on February 13, 1894, to W. J. Barron and has, in certain respects, more resemblance to my unidirectional escapement mechanism than any of the others.

10 I will now briefly analyze the mechanism illustrated in said patent to conclusively show that it is impractical and will, by way of contrast, show the practical characteristics of my invention.

15 The mechanism which is shown in said patent may, for the sake of clarity of explanation and of comparison, be divided into two parts as follows:

19 (A) A double rack and a rotary dog, and
(B) A ratchet wheel and two pawls which I
20 term herein, "converting mechanism."

Rack and dog of Patent No. 514,807

Said patent shows a rack that has two parallel rows of teeth, the teeth in one row being arranged in a staggered order relative to the teeth in the other row.

25 It also shows a dog in the form of a disc having upon its periphery a series of teeth sufficiently spaced apart so that the space therebetween will permit the passage of teeth of said rack.

30 One of the defects of said rack, is the space limitation between the teeth thereof.

As an example of the defect of space limitation, suppose that said rack—and its associated dog, etc.—are to be applied to a typewriter for writing twelve (12) letters to the horizontal inch.

35 One inch (1") divided by twelve (12), is equal to a little over .083". Accordingly the distance between the center of one tooth of said rack and the center of the next tooth (of the other row) thereof will be .083".

40 Said .083" is to cover the thickness of one tooth of said rack, plus the thickness of one tooth of said dog, and plus the clearance between the tooth of said dog and the tooth of said rack.

45 To readily comprehend what is meant by "clearance" let us suppose that we are viewing said rack from the front, and it is adapted to move toward the left as the typing progresses.

50 In this case the left side of a tooth of said rack, is (when the carriage is not moving), against the right side of a tooth of said rotary dog. Obviously, there should be a "clearance" between the left side of said tooth of said dog and the right side of the next tooth of the next row of teeth.

of said rack to enable said dog to rotate without interference.

If said clearance is about .020", the total thickness of a tooth of said rack and a tooth of said dog, will be one sixteenth of an inch ($\frac{1}{16}$ "), or for example the thickness of the teeth of said rack will be one thirty-second of an inch ($\frac{3}{32}$ ").

Furthermore, if said rack were designed for typing sixteen (16) letters to the horizontal inch, and if said clearance were to be, as before, .020", then the thickness of one tooth of the rack plus the thickness of one tooth of the dog, will be .0425".

Such thin teeth on said rack will not only become weaker but are not mechanically feasible if they were made of rollers or rods instead of a flat surface.

(NOTE.—The teeth of my escapement wheel which is shown in Figs. 1, 2, etc., are cylindrical and can each be covered by an anti-friction roller.)

It is very advantageous to use such rollers, or at least rods, to form the teeth of said rack or of said dog, in order to reduce the friction between the teeth of said rack and said dog so as to easily rotate said dog.

Converting mechanism of Patent No. 514,807

Said patent illustrates what I term herein a "converting mechanism." It consists of a ratchet wheel and two pawls and is intended to "convert" the reciprocating stroke of the universal bar into rotary motion for rotating said dog.

Said ratchet wheel is secured to said rotary dog, and one of the two pawls is adapted to propel said ratchet wheel while the other pawl is adapted to prevent said ratchet wheel from turning backward.

While moving back and forth by the typing action, said universal bar actuates said propelling pawl and as a result of this said ratchet rotates one tooth.

Each intermittent rotation of said ratchet by said pawl, rotates said dog one step and allows said rack to advance one-half the distance between two of the teeth in one row.

The main defect of said converting mechanism is speed limitation of said pawl and said ratchet wheel. It is too slow for the modern high speed typewriters.

Everything else being equal, the speed of operation of an escapement mechanism is the predominant and deciding factor.

Another important defect of said escapement mechanism or rather said double rack, is in the mechanism employed therein for returning the carriage to the left hand marginal alignment. It simply does not respond to the high speed requirements of modern typing machines.

Now, from the description given above, it can be seen that said Patent No. 514,807 is impractical.

My unidirectional escapement mechanism

My unidirectional escapement mechanism is different from and superior to the unidirectional escapement mechanism which is illustrated in said Patent No. 514,807, in many respects.

The mechanism of my unidirectional escapement, the subject of the present invention, is, for the sake of clarity of explanation and of comparison, divided into two parts as follows:

(a) A double escapement wheel and a rotary dog; and

(b) A novel and high speed "converting mechanism."

My escapement wheel and dog

In the preferred form of my invention I provide an escapement wheel which has two spaced parallel rows of teeth. The same number of teeth are employed in each row, and the spacing of the teeth in each row is uniform. The teeth in one of said rows are so positioned that if a line were drawn through any one of its teeth parallel to the axis of said wheel it will bisect the interval between two teeth of the other row. This means that any tooth in one row is in axial alignment with the center of the space between two teeth of the other row, as shown in Figures 1 and 2. This arrangement of teeth will be hereinafter called "staggered."

Cooperating with this escapement wheel is a single rotary dog, having teeth somewhat similar to the teeth of a gear, each tooth being adapted to engage the teeth of said rows alternately.

The width of each tooth of the toothed dog is substantially equal to the axial space between a plane extending through the centers of the teeth in one of said rows on the escapement wheel and a plane extending through the centers of the teeth in the other of said rows, as shown in Figure 5.

Normally, the center of one of the teeth of said dog is in contact with the center of one of the teeth of one or the other of the two rows on the escapement wheel, thereby preventing the escapement wheel from rotating under the urge of the main spring. This is clearly shown in Figure 1.

During typing action the universal bar rotates said dog one-half of the distance between the centers of two adjacent teeth of said dog. The half-tooth interval of movement of said dog, by said universal bar, displaces the tooth of the dog from contact with a given tooth in one row on the escapement wheel with which it was in contact and moves it into the path of the teeth of the other row on the escapement wheel. Accordingly, the next adjacent space between said tooth (of the dog) and the next one to it comes into and remains across the path of said given tooth leaving it free to move therethrough. Since the escapement wheel is rotatably urged by the main spring of the carriage, it does rotate until it is arrested by the engagement of the next tooth, in said other row, with the intercepting tooth of the dog. Thus, the escapement wheel, in a single movement, effects the movement of the carriage one letter-space.

By the expression "one-half of a tooth interval" I mean one-half of the width of a tooth plus one-half of the width of the space between that tooth and the next adjacent one. For example, the dog shown in Figures 1 and 2 has 12 teeth and 12 spaces therebetween. Therefore, it will move in 24 steps for each complete revolution thereof, each step effecting a letter spacing of the carriage.

One of the advantages and superior features of my escapement wheel is this: there is no space limitation between the teeth thereof. This enables the choice of space intervals between the teeth of my escapement wheel according to the various factors involved.

For example, the teeth of my escapement wheel may be made cylindrical as shown in Figures 1, 2, etc., so as to reduce frictional contact between the teeth of my escapement wheel and the teeth of my dog. Being not restricted to space limitation, the cylindrical teeth may be made as strong as required.

To further reduce said frictional contact, anti-

friction rollers (not shown) may be mounted upon said cylindrical teeth.

The absence of space limitation between the teeth of my escapement wheel is superior not only to the rack of said patent but also to the escapement wheel of prevailing typewriters, for said last mentioned escapement wheel requires, due to its loose and rigid dogs, a comparatively large interval between said teeth.

Converting mechanism of my escapement

My converting mechanism, the mechanism which transforms the reciprocal movements of the universal bar into stepped rotation of my rotary dog, consists of:

(A) A ratchet wheel which is secured to my rotary dog and which has twice as many teeth as said dog has, so that the rotation of one tooth of said ratchet wheel rotates said dog one-half of one tooth.

(B) An oscillatory unit which is termed herein a propelling-unit, and which is adapted to propel or rotate said ratchet wheel.

Said propelling-unit includes two links termed herein toothed-link and shifting-link, respectively.

Said shifting-link is pivoted to the frame of my escapement mechanism while said toothed-link is pivotally mounted on the open end of said shifting-link.

Each of said links is adapted to be motivated in an ordered sequence in relation to the reciprocal strokes of said universal bar.

Any motion which may be imparted to said toothed-link may or may not affect said shifting-link, but any motion which may be imparted to said shifting-link, but any motion which may be imparted to said shifting-link will impart a relative motion to said toothed-link.

(C) A driving-unit which is adapted to drive said propelling unit. It is pivoted on the frame of my escapement mechanism and adapted to be oscillated by the reciprocating strokes of said universal bar.

Said driving-unit carries two selectors, one of which is adapted to motivate said toothed-link, and the other one of which is adapted to motivate said shifting-link.

Thus, both said propelling-unit and said driving-unit are pivotally mounted on the frame of my escapement mechanism.

Said propelling-unit and said driving-unit together, are termed herein "differential-pawl," as if they were a single unit.

As shown in Figure 4, my differential-pawl, is on its return stroke, not in contact with my ratchet wheel, therefore both the teeth of said ratchet wheel and the tooth of said toothed-link may be in the form of either ratchet teeth or any other suitable teeth. However, the teeth of said ratchet wheel are made ratchet-like. This enables the application to said ratchet wheel (not shown) of an additional pawl of the ordinary type, together with my differential-pawl.

Again as shown in Figure 4, the tooth of said toothed-link is made in the form of a stud so as to reduce the friction between it and the teeth of said ratchet wheel. To further reduce said friction an anti-friction roller (not shown) may be mounted on said stud.

Operation of my converting mechanism

In its forward stroke, the universal bar swings said driving-unit in a clockwise direction as viewed from the right side of a typewriter, and

said driving-unit first swings said toothed-link and then it swings said shifting-link.

Each oscillation of said differential-pawl (driving-unit and propelling-unit) rotates said ratchet wheel one tooth. The rotation of said ratchet wheel one tooth interval, rotates my dog one-half of a tooth interval. Each half tooth rotation of my dog enables the carriage to advance a full letter-space.

10 In its forward stroke said driving-unit engages said toothed-link and swings it in a counter-clockwise direction, causing said ratchet to rotate one step in a clockwise direction.

After having propelled said ratchet wheel a given degree, said toothed-link disengages from said ratchet wheel, and from said driving-unit.

While said toothed-link is being disengaged from the tooth of said ratchet, the driving-unit, being still rotating in said clockwise direction, 15 swings said shifting-link which in turn shifts said toothed-link so far away from said ratchet wheel as to be enabled to swing back, under the tension of its spring, in a clockwise direction to a fixed stop without touching said ratchet wheel.

20 25 In its clockwise return direction, said toothed-link does not follow the reverse of the path that it had traced in its counter-clockwise direction. This is due to the shifted pivotal point of said toothed-link by said shifting-link.

30 35 As said universal bar returns to its normal position said driving-unit follows it and returns to its normal position.

The driving-unit, as it is returning toward its normal position, releases said shifting-link, 40 which had been swung under the pressure applied thereto by one of the selector arms of said driving-unit; and as a result of this said shifting-link, under the urge of a spring, returns to its normal position.

45 40 The shifting-link, as it is returning to its normal position, shifts back said toothed-link to its normal position along a path differing from said clockwise path, from said shifting path which followed said clockwise path and from said counter-clockwise path.

50 55 Thus, in each oscillation of said driving-unit, the toothed end of said toothed-link traverses a somewhat quadrilateral path, comprised of said clockwise path, said downward shifting path, said counter-clockwise path, and said upward-shifting path.

In its upward shift the tooth of said toothed-link, enters into the space between two teeth of said ratchet wheel in alignment therewith.

55 60 Now, it can be seen that the path of said upward shifting of said toothed-link, is at an angle (for example, nearly a right angle) to said counter-clockwise path along which said toothed-link passes to rotate said ratchet wheel. That is, said toothed-link reengages the space of the teeth of said ratchet wheel in a different direction than the direction in which it rotates said tooth. This enables my differential-pawl to engage and rotate said ratchet wheel as fast as any typist reciprocates said universal bar while typing.

Shifting means of my differential-pawl

An important and novel feature of my differential-pawl is the system and mechanism for shifting said toothed-link toward and away from said ratchet wheel.

Both the time of shifting said toothed-link and the angle the same is shifted in relation to the teeth of the ratchet wheel from which it is shifted out downwardly, or toward which it is shifted

upwardly, have an important bearing upon the operation of my converting mechanism.

The time and the speed of shifting of said toothed-link is, as can be seen from Figure 4, determined by the relative distance between said driving-unit and said propelling-unit. The sooner after the beginning of the oscillation of said propelling-unit the driving-unit contacts said shifting-link, the sooner said toothed-link is shifted out from or disengaged from said ratchet wheel. And the nearer the point of contact of said driving-unit with said shifting-link is to the pivot of the latter, the faster said toothed-link is shifted out from said ratchet wheel.

The angle of shifting said toothed-link in relation to the teeth of the ratchet wheel varies in accordance with the variation of several factors such as, for example, the position of the pivot of said shifting-link on said frame, the length of said shifting-link, the length of said toothed-link, etc.

Any change in said factors may, and often will, change the angle between said shifting-link and said toothed-link. Any change of the angle between said shifting-link and said toothed-link may, and often will, change the path of shifting of said toothed-link towards and from said ratchet wheel. And any change of the path of said toothed-link in relation to the teeth of said ratchet wheel, may, and often will, affect the ease, the speed and the accuracy of operation of my converting mechanism.

Obviously, the easiest and the most accurate way of shifting said toothed-link in and out, is along a radial line, that is, along a straight line passing through the centers of said toothed-link and said ratchet wheel.

In the preferred form of my invention the position of the pivot of said shifting-link on the frame, the length of said shifting-link, the length of said toothed-link, etc., are so devised that if, at least at one position of contact between said toothed-link and said ratchet wheel, a radial line is drawn from the center of said ratchet wheel across the center of said toothed-link and it is extended beyond said toothed-link it will pass through the center of the pivot of said toothed-link on said shifting-link.

Features of my escapement mechanism

Some of the important features of my escapement mechanism are as follows:

(A) All parts and elements of my escapement mechanism, including all links of my differential-pawl, are pivoted on their respective centers so as to minimize their operative frictions. No pushing or pulling element is used. To further reduce their operative friction ball bearings, thrust bearings, etc. (not shown), may be applied to said pivots.

(B) The contact between all cooperative elements and parts of my escapement mechanism is adapted to be made by studs so as to minimizes their operative frictional contact.

For example, a stud or stub shaft is carried on the open end of said toothed-link. It is extended outwardly from both the front and the rear faces of said toothed-link. The extended part of said stud from the rear face of said toothed-link is adapted to serve for a tooth to engage and rotate said ratchet wheel, while the extended part of said stud from the front face of said toothed-link, is adapted to be engaged and driven by the driving-unit.

Anti-friction rollers (not shown) may be mounted on each and all of said studs to reduce their frictional contact to a minimum.

(C) The driving-unit, swinging in clockwise direction on its forward stroke, oscillates said toothed-link in counter-clockwise direction. The selecting arm of said driving-unit contacts said external stud just slightly below the center of the same, and consequently the tendency of said driving-unit is to rotate said stud in said clockwise direction (which is the direction of rotation of said driving-unit), thereby enabling the holding of said stud in cooperative contact with the tooth of said ratchet wheel by means of a light spring.

(D) The disengaging of my toothed-link from its ratchet wheel, is effected at a position where the path of rotation of said toothed-link due to its counter-clockwise direction, diverges from the path of rotation of said ratchet which rotates in clockwise direction. Due to its diverging path said toothed-link while approaching the position where it is disengaged from the tooth of said ratchet, decelerates the rotation thereof.

(E) In its forward stroke my differential-pawl will rotate my ratchet wheel until said stud is disengaged from said ratchet wheel; thereupon any additional or overthrow stroke of my said differential-pawl cannot affect the rotation of said ratchet wheel, and accordingly any overthrow of said universal bar, will simply shift said toothed-link farther away from said ratchet wheel, without, however, affecting the rotation of said ratchet wheel.

(F) On its return stroke, said toothed-link being out of contact with my ratchet wheel, eliminates frictional contact between itself and said ratchet wheel, hence I call it a "free return" link or pawl.

(G) Again, on its return stroke, said toothed-link being out of contact from said ratchet wheel, requires only a light spring to swing it back in clockwise direction.

(H) As it is being reengaged with the tooth of my ratchet wheel, said toothed-link moves, somewhat radially, into engagement with said ratchet wheel, whereby rebounding, vibration, etc., will not affect said engagement in any manner.

(I) No space limitation between the teeth of either my escapement wheel or my rotary dog, so that teeth of any suitable outline and dimension such as, for example, rods or other forms of teeth, which are shown in the accompanying drawings may be used to reduce the frictional contact between the teeth of my escapement wheel and my rotary dog.

(J) The possibility of applying anti-friction rollers (not shown) on said rods (teeth) to further reduce or minimize frictional contact between the teeth of my dog and my escapement wheel.

(K) The absence of any particular requirement for setting the universal bar into operation by typing action, as my escapement mechanism operates under any and all sorts of typing strokes.

Referring to the drawings, which are given by way of example:

Figure 1 is a diagrammatic representation of a typewriter, a portion of which is broken away to show my new and improved escapement mechanism in elevation as seen along the lines 1—1 of Figure 2;

Figure 2 is a view of my escapement mechanism as seen along the lines 2—2 of Figure 1;

Figure 3 is a plan view of my escapement dog means, together with elements cooperating therewith, taken along the lines 3—3 of Figure 1;

Figure 4 is a series of step diagrams, each taken along the lines 4—4 of Figure 2, and showing the action of ratchet means on the escapement dog means and its relation to the universal bar on the typewriter;

Figure 5 is a fragmentary view showing the width of the teeth in my escapement dog means with respect to the center lines of the two rows of teeth on my escapement wheel;

Figure 5a is a fragmentary view showing the width of the spaces between the teeth in my escapement dog means with respect to the center lines of the two rows of teeth on my escapement wheel;

Figures 6 and 6a are charts showing the relation between the teeth on the dog of the form shown in Figures 1 to 5 inclusive, and the teeth in the double row on the escapement wheel and the movement effected thereby;

Figure 7 is a front elevation of a modification wherein the escapement wheel has a single row of teeth and the escapement dog has a double row of teeth;

Figure 8 is a side elevation taken along the lines 8—8 of Figure 7; and

Figure 9 is a plan view taken along the lines 9—9 of Figure 8.

Referring first to Figures 1 and 2, the typewriter includes a frame 20, keys 21, type bars 22, a universal bar 23, and a carriage 24, upon which is mounted a platen 25 and a rack 26. The carriage is urged toward the left, as seen in Figure 2, by means of a main spring 27 carried in a spring drum 28 and having a flexible extension 29 which is connected to the carriage 24.

A pinion 30 is keyed to the escapement wheel shaft 31, and secured to the pinion 30 is a ratchet wheel 39. My escapement wheel 33 is comprised of two discs 34 and 35 connected together by a hub 36 which is freely journaled on the shaft 31. The shaft 31 is carried on supports 37 and 38. The ratchet wheel 39 is connected to the pinion 30 by means of a hub 40 and it normally abuts the face of the disc 35. Journaled on a stud 41 in the disc 35 is a pawl 42 which engages the teeth of the ratchet wheel 39 and constitutes the driving link between the pinion 30 and the escapement wheel 33. Cooperating with the ratchet wheel 39 is a push rod 43 which is actuated by the back space key on the typewriter. This push rod advances the ratchet wheel 39 one tooth when the back space key is depressed, thereby causing the pawl 42 to ride over into the next tooth. The ratchet also allows the carriage to be returned.

For simplicity in describing the cooperation of the escapement wheel and the escapement dog to be presently described, the teeth of the escapement wheel are numbered so as to distinguish each tooth in each of the two rows. In other words, the teeth on the disc 34 are numbered 44a, 44b, 44c, 44d, 44e and 44f, while the teeth on the disc are numbered 44A, 44B, 44C, 44D, 44E and 44F.

My dog device includes a wheel 45 which is provided with a plurality of teeth 46 with equal spaces 47 therebetween.

From Figure 5 it will be noted that the width of each tooth 46, and consequently of each space 47, is determined by the spacing of the discs 34 and 35 of the escapement wheel. It will be

noted from this figure that the width of the tooth 46 at the periphery is equal to the space between the center line 34a of the disc 34 and the center line 35a of the disc 35.

The dog wheel 45, referring now to Figure 2, has formed integral therewith a hub 48 which joins a ratchet wheel 49 having ratchet teeth 50 thereon. The structure comprising the dog wheel 45, the hub 48 and the ratchet wheel 49 is journaled on a shaft 51 which has one end supported in a suitable hole formed in a boss 52 carried on the upper end of an upright support 53. The other end of the shaft 51 is supported in a similar boss 54 carried on an upright support 55. The upright supports 53 and 55 are joined by a horizontal portion 56 which may be secured to the frame 20 in any suitable manner, for example, by means of screws 57.

Driving unit

The following elements comprise what I term my driving unit:

An arm 58 has a hub 59 which is also journaled on the shaft 51. The hub 59 has an enlarged portion 60 which abuts the ratchet wheel 49, and thereby the arm 58 is held in spaced relation to the ratchet wheel 49. Formed integral with the hub 59 is a sector 61, the radius of which is longer than the radius of the ratchet wheel 49. Formed integral with the sector 61 is a second sector 62, the radius of which is substantially longer than the radius of the sector 61. The arm 58 has a stud 63 extending to the left, as seen in Figures 2 and 3, and toward the rear, as shown in Figure 4, and journaled on this stud is a roller 64 which is adapted to be engaged by the end of the universal bar 23.

The arm 58 is normally positioned against a stop pin 89 and it is urged into engagement with the stop pin 89 by means of a spring 90, one end of which is secured to the arm 58 and the other end of which is secured to the upright support 55. The sector 61 has an active radial face 61a, and likewise the sector 62 has an active radial face 62a.

These elements comprise a driving unit which is actuated by the universal bar and which, in turn, actuates the shifting link of my propelling unit, to be presently described.

An upright member 65 has a base 66 which is secured to the horizontal portion 56 between the uprights 53 and 55 by means of screws 67.

Shifting link

My shifting link is comprised of the following elements:

A lever 70 is journaled on a stud 68 carried by the upright support 55, as may best be seen in Figure 4. This lever has a normally horizontal portion 69, and formed integral therewith on the right end thereof is a normally vertical portion 71. The vertical portion carries a stud 72, which may best be seen in Figure 3, and carried on this stud is a ball bearing 73, which includes an inner race 74, a plurality of balls 75, and an outer race 76 which cooperates with the arcuate face of the sector 62.

The lever member 70 has one end of a spring 77 secured thereto, and the other end of this spring 77 is secured to the horizontal portion 56 of the support. Consequently, the lever member 70 is urged in a clockwise direction about the axis 68 into contact with an eccentric 78. This eccentric, as may be seen in Figure 2, has a hub 79, which abuts the upright portion 55 of the support and which is secured thereto by means of

a screw 80. By means of the screw 80, the eccentric may be adjusted and set so as to form a stop for the lever member 70 in any desired position within the throw of the eccentric. Also carried on the horizontal portion 69 of the lever member is a stud 81, which has journaled thereon a roller 82.

Toothed link

An arm 83 is rotatably mounted on the horizontal portion 69 of the lever 70 by means of a shouldered screw 84. This arm has an extension 85, to which one end of a spring 86 is secured. The other end of the spring 86 is secured to a depending tab 87, which is preferably formed integral with the horizontal portion 69. The arm 83 carries, near its outer extremity, a shaft 88. A portion 88a cooperates with the teeth 50 of the ratchet wheel 49 and also with the sector 61. The other portion 88b of the shaft 88 cooperates with a stop shown herein as the upright 65 which defines the "at rest" position of said link. The arm 83 and its shaft 88 and the portion 88b thereof constitute my toothed link. The functions of said toothed link will be explained in detail in connection with the six steps shown in Figure 4.

Propelling unit

The elements of my shifting link, described above, and the elements of my toothed link carried on the shifting link, constitute what I term herein my propelling unit, because they take the reciprocating motion of the universal bar, via my driving unit, and deliver it to the ratchet wheel 49, causing the latter to rotate in steps.

Operation of the ratchet wheel 49

When a key such as the key 21 is depressed, a type bar such as the type bar 22 is moved toward the platen in the usual manner. During that time, the universal bar 23 moves toward the right, as seen in Figures 1 and 4. Referring more particularly to Figure 4A, I show the ratchet wheel 49 and its cooperative elements in their normal positions. The arm 58 of the driving unit is held in contact with the stop pin 89 by means of the spring 90; and the arm 83 of the toothed link is at rest, with its shaft portion 88b in contact with the upright 65, and with 88a in contact with the radial face 61a of the sector 61 of the driving unit. The lever member 70 of the shifting link is in contact with the eccentric 78, due to the urge of the spring 77, and the ball bearing 73 is in contact with the arcuate face of the sector 62 of the driving unit.

Now, breaking down the advance of the universal bar: In Figure 4B the universal bar 23 has advanced slightly. The end of this bar has engaged the roller 64 and has advanced the arm 58 of the driving unit slightly in a clockwise direction. The radial face 61a of the sector 61 of the driving unit has engaged the shaft 88, which is the tooth of my toothed link, and moved it into engagement with the ratchet wheel tooth 50a. It will also be noted that the sector 62 on the driving unit has moved downwardly a corresponding amount, and the ball bearing 73 on the shifting link is in contact with the curved surface of said sector 62 at a point nearer to the mid portion thereof.

In Figure 4C, the arm 58 has been pushed by the universal bar 23 to a position where it is almost vertical. In this position the radial edge 61a of the sector 61 on the driving unit has moved the shaft 88 on the toothed link and the arm 83 supporting it in a counter-clockwise direction to

a point where the shaft 88 is just about to leave the ratchet tooth 50a, thereby tensioning the spring 86. By this movement, the ratchet tooth 50a has advanced in a clockwise direction a distance equal to one tooth. The sector 62 on the driving unit has moved downwardly to a point where the ball bearing 73 on the shifting link is in contact with the upper portion of the curved surface 62 of the driving unit and is almost ready to pass off of the same.

In Figure 4D, the arm 58 has been pushed by the universal bar 23 to a position beyond the vertical plane, the shaft 88, which is the tooth of the toothed link, is in contact with the arcuate surface of the sector 61 of the driving unit, and the arcuate surface of the sector 62 of the same unit has been moved out of contact with the ball bearing 73 on the shifting link, and its radial face 62a is in contact with the roller 82 on the lever member 70 of the shifting link. Since the shaft 88 (or tooth) has been cammed downwardly by the sector 61, it has left the tooth 50a in a position where the tooth has been advanced a space equal to the distance from one tooth to the other of the ratchet wheel 49, and the lever member 70 of the shifting link is still held in contact with the eccentric stop 78 by means of the spring 77.

Referring to Figure 4E, the arm 58 has been still further advanced by the universal bar 23, and the radial face 62a of the sector on the driving unit, acting against the roller 82, has swung the lever member 70 of the shifting link about the axis 68 in a counter-clockwise direction. Due to the fact that the radius between the axis 81 of the roller 82 and the axis 68 supporting the lever member 70 is short, this movement has been substantial, and the arm 83 of the toothed link, it is assumed, has not yet been moved in a clockwise direction under the urge of the spring 86.

Referring now to Figure 4F, which shows the bar array an instant later, the spring 86 has moved the arm 83 in a clockwise direction until it has been arrested by the contact of the shaft 88 of the toothed link with the vertical support 65. When the universal bar returns, the arm 58 of the driving unit, under the urge of the spring 90, returns to its normal position in contact with the stop 89. The sectors 61 and 62 also return to their normal positions, which are the positions shown in Figure 4A.

Now, since the radial face 62a of the sector 62 is by this movement disengaged from the roller 82, the lever member 70 of the shifting link is snapped back to its normal position, in contact with the eccentric 78, under the urge of the spring 77. However, the sector 62 of the driving unit, in moving to its normal position, prevents the lever member 70 of the shifting link from rebounding, due to the engagement of the ball bearing 73 with the arcuate surface of the sector.

The shaft 88 of the toothed link, which was urged into contact with the vertical support 65, by means of the spring 86 described above, may rebound as it strikes the support 65; but, as noted from Figure 4F, an arc 86a drawn from the point of the tooth 50b about the axis 68 shows that, even with substantial rebounding of the shaft 88, this shaft or tooth is certain to pass into the space between the teeth 50b and 50c as the lever 70 returns to its normal position.

Operation of the escapement

Due to the fact that the ratchet wheel 49 and the escapement dog wheel 45 are connected to

gether by the hub 48 to form a unitary structure, the movement of said ratchet wheel 49 one tooth, causes the escapement dog wheel 45 to advance one-half tooth.

Referring to Chart A in Figure 6, the dog 45 is at rest and the escapement wheel 34, 35 is at rest. This is the position shown in Figure 1. Charts B, C and D in Figure 6 show the breakdown of the movements of the elements while effecting one complete letter space. As a key is being depressed, the escapement dog wheel tooth 46a is moved from the position shown in Chart A of Figure 6, where the escapement wheel tooth 44a in the row 34 is arrested. Now this dog tooth must arrest the next escapement wheel tooth in the second row to effect a letter spacing, and during the first portion of the movement of the dog tooth 46a it has moved to a position where its extremities coincide with the center lines of the two rows of escapement wheel teeth, the position shown at Chart B in Figure 6, which is also the position shown in Figure 5. In this position the escapement wheel is still locked against movement because the dog tooth 46a has not yet moved out of the path of the escapement wheel tooth 44a. In Chart C of Figure 6 the escapement dog tooth 46a has completed its movement and is in alignment with the tooth 44A in the row 35 of the escapement wheel, and at the same time the space 47b between the dog teeth 46a and 46b is in alignment with the teeth of the escapement wheel in the row 34, so that the tooth 44a is free to pass through this space, and when it does so the escapement wheel is arrested as soon as the escapement wheel tooth 44A contacts the dog tooth 46a. This is the position shown in Chart D of Figure 6. The dog tooth 46a remains still and the escapement wheel is arrested thereby by the engagement of the tooth 44A with it. Thus one complete letter space is effected.

It will be noted that during the first part of this movement the escapement dog rotates, and during the latter part of this movement the escapement wheel moves and the escapement dog comes to rest and arrests the escapement wheel. Charts E, F and G of Figure 6 show a breakdown of the movements of the elements for effecting a second complete letter-space. In Chart E the escapement dog has rotated to a position where the extremities of the space 47b between the teeth 46a and 46b are in alignment with the center lines of the two rows of teeth on the escapement wheel. It will be noted, however, that the tooth 46a is still in engagement with the escapement wheel tooth 44A. Now as the escapement dog rotates further, the space 47b, as shown in Chart F, is brought into alignment with the escapement wheel tooth 44A and the latter is free to move therethrough. At the same time, the dog tooth 46b is moved into alignment with the row of escapement wheel teeth 34 so as to arrest the escapement wheel tooth 44b. In Chart F it is assumed, for purposes of illustration, that the escapement wheel has not yet started to move. However, it does move because the tooth 44A on the escapement is free to move through the space 47b and the tooth 44b in the row 34 of the escapement wheel comes against and is arrested by the dog tooth 46b, as shown in Chart G, and thus a second complete letter-space is effected.

As a matter of fact, the dog wheel starts moving while the escapement wheel is locked against movement. The dog wheel releases the escapement wheel and comes to rest, and the escape-

ment wheel moves until one of its teeth in one or the other of said rows is arrested by the one of the dog wheel teeth which is in its path.

The chart Figure 6a shows the relation between the teeth of the dog and the teeth of the escapement wheel at rest. The first position A represents the initial position of the carriage. The Chart D shows the relation of the teeth of the escapement dog and the escapement wheel when one unit of letter space has been effected, and the Chart G shows the relation of the escapement dog and escapement teeth when a second unit spacing of the carriage has been effected.

Modification

Figures 7, 8 and 9 show a modification of the form of the device shown in Figures 1 and 2. The ratchet wheel and the cooperative driving unit and the propelling unit for changing the reciprocating movement of the universal bar into intermittent motion in one direction, may be the same as that described above and I show those elements as designated by the same numerals and/or symbols as were applied thereto in connection with the description of Figures 4A, B, C, D, E and F, consequently the description need not be repeated.

In this embodiment of the invention, I provide the escapement wheel with a single row of teeth and the dog wheel with two rows of teeth. The escapement wheel 104 is journaled on the shaft 31 and carries the pawl 42 which engages the ratchet wheel 39 in the same manner as in the arrangement shown in Figures 1 and 2. The escapement wheel carries teeth 92, each of which comprises a shank 93 with a ball 94 on the outer extremity thereof, arranged in a single row. For convenience these teeth are designated as 92, 92a, 92b, 92c, etc.

Cooperating with the escapement wheel 104 is an escapement dog wheel 95 which is comprised of a disc 96, and a second disc 97 spaced apart therefrom by a hub 98 preferably formed integral with the discs to form a unitary dog wheel. This dog wheel may be integral with or positively fixed to a second hub 99 which carries the ratchet wheel 49. This array is journaled on the shaft 51, and as the ratchet wheel is advanced, as described in connection with Figures 4A to 4F, the escapement dog wheel 95 is advanced.

The disc 96 has teeth 100 formed thereon with spaces 101 therebetween, the teeth and the spaces all being of the same width. The disc 97 has teeth 102 formed thereon with spaces 103 therebetween. The teeth on each disc are in axial alignment with the spaces on the other.

Operation

Referring to Figure 9, the escapement wheel tooth 92 is normally arrested by the dog tooth 100 on the disc 96. Now when a key is depressed and the universal bar advances the ratchet 49 and, consequently, the dog wheel 95 one step, the dog tooth 100 is moved in the direction of the arrow, Figure 9, to the position which the space 101k had just previously occupied. Coincident with this movement, the tooth 102 in the other row moves from the position shown in Figure 9 to the position of the space 103k. Now as the trailing edge of the dog tooth 100 comes into alignment with the center line of the escapement tooth 92, the leading edge of the dog tooth 102 also comes into alignment with the center line of the escapement tooth 92, and as the dog wheel continues to move, the trailing edge of the dog tooth 100 clears the right edge of the ball on

the escapement tooth 92, and it is free to move in the direction of the arrow. By the time the dog tooth 100 has cleared the escapement tooth, the dog tooth 102 has overlapped the path of the escapement tooth 92, so the tooth 92 is arrested by the dog tooth 102 as it is released by the dog tooth 100, and the movement of the escapement wheel, resulting from the movement of its tooth 92 from the point where it is released by the dog tooth 100, to the point where it is arrested by the dog tooth 102, effects one full, complete letter-space in a single movement of the carriage controlled by the escapement mechanism.

During the next movement of the universal bar to effect a second letter-space, the dog tooth 102 moves to the right one step and releases the escapement tooth 92. At the same time, the dog tooth 100a moves into the path of and arrests the escapement wheel tooth 92a.

From the above description it will be seen that, in the first form described, the escapement wheel has teeth arranged in staggered fashion in two rows, and the dog wheel has its teeth arranged in a single row, while in the modification the escapement wheel has its teeth arranged in a single row and the dog wheel has its teeth arranged in two rows. This means that one escapement element has teeth arranged in two rows while its cooperative element has teeth arranged in a single row.

It will be understood that I am not limited to the exact details of the above described arrangements, as many changes may be made in such arrangements within the scope of the appended claims.

I claim:

1. In a typewriter, a carriage, a universal bar moved by typing action, an escapement mechanism operatively connected to said carriage and including in combination a rotatable escapement wheel and a rotatable dog wheel, one of said wheels carrying a single row of teeth on its periphery while the other one carries two parallel rows of teeth on its periphery, the teeth in one of said last rows being disposed in a staggered order relative to those in the adjacent row, said wheels being mounted on shafts at right angles to each other so that said dog wheel forms an intermittently rotatable limiting stop against the rotation of said escapement wheel, a ratchet wheel movable with said dog wheel, a driving unit actuated by said universal bar, and a propelling unit actuated by said driving unit and including a toothed link cooperating with said ratchet wheel.

2. In a typewriter, a frame, keys on said frame, a carriage movable on said frame, a universal bar moved by the action of said keys, an escapement mechanism operatively connected to said carriage and including a rotatable escapement wheel and a rotatable dog wheel meshing with each other and having supporting shafts in said frame with their axes 90° apart, one of said wheels having a single row of teeth on its periphery while the other one of said wheels has two parallel rows of teeth on its periphery, the teeth in one row thereon being staggered with respect to and substantially spaced apart from those in the adjacent row, a ratchet wheel keyed to the shaft of said dog wheel, a propelling unit on said frame and including a toothed link cooperating with said ratchet wheel, and a driving unit for said propelling unit pivoted on said frame in cooperative relation with said universal bar.

3. In a typewriter, a frame, keys on said frame, a carriage movable on said frame, a universal bar

on said frame moved by the action of said keys, an escapement mechanism including a rotatable escapement wheel and a rotatable dog wheel, one of said wheels having a single row of teeth on its periphery and the other having two parallel rows of teeth on its periphery, the teeth in one of said last rows being staggered with respect to the teeth in the other, the interval between the centers of the teeth of said escapement wheel being sufficiently large for said teeth to have substantial thickness and outline with sufficient space between said teeth for the teeth of said dog wheel to also have substantial thickness and outline, individual shafts journaled in said frame and supporting said wheels, means operatively connecting said escapement wheel to said carriage, a ratchet wheel keyed to the shaft of said dog wheel, a propelling unit on said frame including a toothed link cooperating with said ratchet wheel, stop means on said frame forming a reference point for said link, and a driving unit on said frame operatively connected to said propelling unit and actuated by said universal bar.

4. In a typewriter, a frame, keys on said frame, a carriage movable on said frame, a universal bar moved by the action of any of said keys, an escapement mechanism operatively connected to said carriage and including a rotatable escapement wheel and a rotatable dog wheel, one of said wheels carrying on its periphery a single row of teeth and the other wheel carrying on its periphery two spaced parallel rows of teeth, the teeth in one row being staggered relative to those in the other, the space between the teeth of said escapement wheel accommodating the thickness of the teeth of said dog wheel plus a minimum clearance for reducing shock, noise, and wear such as are present in other types of typewriters where the clearance is, of necessity, large, individual shafts journaled in said frame and carrying said wheels, a ratchet wheel secured on the shaft of said dog wheel, and high speed pawl means and controls therefor between said universal bar and said ratchet wheel effective to advance said wheel during the forward movement of said universal bar.

5. In a typewriter, a frame, keys on said frame, a carriage movable on said frame, a universal bar moved by any of said keys, an escapement mechanism operatively connected to said carriage and including a rotatable escapement wheel and a rotatable dog wheel, individual shafts journaled in said frame and supporting said wheels, one of said wheels carrying on its periphery a single row of teeth, and the other of said wheels carrying on its periphery two spaced parallel rows of teeth, the teeth in one row being staggered relative to those in the other, the width of each tooth on one of said wheels at the periphery thereof being equal to the width of the space between itself and its neighbor, a ratchet wheel carried on the shaft of said dog wheel, and high speed pawl means and controls therefor between said ratchet wheel and said universal bar effective to advance said ratchet wheel during a predetermined portion of the forward movement of said universal bar.

6. In a typewriter, a frame, keys on said frame, a carriage movable on said frame, a universal bar movable forward and back as a result of key action, an escapement mechanism operatively connected to said carriage and including a rotatable escapement wheel and a rotatable dog wheel, one of said wheels carrying a single row of teeth on its periphery, and the other of said

wheels carrying two spaced parallel rows of teeth on its periphery, the teeth in one of said last rows being staggered with respect to the teeth in the other, the width of each tooth on one of said wheels being substantially equal to the distance between the centers of two adjacent teeth on the other wheel, individual shafts journaled in said frame and supporting said wheels, a ratchet wheel carried on the shaft of said dog wheel, and high speed pawl means actuated by said universal bar during a predetermined portion of the forward movement thereof, said pawl means including a toothed link normally engaged with said ratchet wheel and disengaged therefrom during said predetermined portion of said forward movement.

7. In a typewriter, a frame, keys on said frame, a carriage movable on said frame, a universal bar movable forward and back as a result of key action, an escapement mechanism operatively connected to said carriage and including a rotatable escapement wheel and a rotatable dog wheel, a single row of teeth carried on the periphery of one of said wheels, and two spaced parallel rows of teeth carried on the periphery of the other of said wheels, the teeth in one row on said last wheel being staggered relative to the teeth in the other row, and the width of the teeth on one of said wheels being substantially wider than the teeth on the other, individual shafts journaled in said frame and supporting said wheels, a ratchet wheel carried on the shaft of said dog wheel, and high speed pawl means actuated by said universal bar during a predetermined portion of the forward movement thereof, said pawl means including a toothed link normally engaged with said ratchet wheel and disengaged therefrom during said predetermined portion of said forward movement.

8. In a typewriter, a frame, keys on said frame, a carriage movable on said frame, a universal bar movable forward and back as a result of key action, a unidirectional escapement mechanism operatively connected to said carriage and comprising a rotary dog wheel having peripheral teeth thereon, a ratchet wheel operatively connected to said dog wheel and having twice as many teeth as said dog wheel has, a driving unit moved by said universal bar, said driving unit having a first and a second cam means, a shifting unit pivoted on said frame and actuated by said first cam means, and a toothed-link pivoted on said shifting unit in cooperative relation with said ratchet wheel and adapted to be actuated directly by said second cam means and indirectly by said first cam means acting against said shifting unit, each oscillation of said driving-unit being adapted, through said driving unit and said shifting unit, to cause said toothed-link to effect the following steps sequentially; the rotation of said ratchet wheel a given degree, the disengagement from said ratchet wheel, the swinging backwardly, and the reengagement with the next adjacent tooth on said ratchet wheel.

9. In a typewriter, a frame, keys on said frame, a carriage movable on said frame, a universal bar movable forward and back as a result of key action, a unidirectional escapement mechanism operatively connected to said carriage and comprising a rotary dog having a plurality of teeth disposed about the periphery thereof, a ratchet wheel secured to the axis of said dog and having twice as many teeth as said dog has, a toothed-link adapted to oscillate about a plurality of pivots and normally in operative engagement with said ratchet-wheel, a shifting unit

pivoted on said frame and having said link pivoted thereon, thereby providing said plurality of pivots, a driving-unit having a first cam thereon and a second cam thereon, said first cam being arranged to actuate said toothed-link directly and said second cam being arranged to actuate said shifting unit, and a universal bar to actuate said driving-unit, each oscillation of said driving-unit being adapted, through the medium of said cams, to swing said toothed-link about said pivots sequentially for causing the same to rotate said ratchet wheel a given degree, to decelerate the rotation of said ratchet wheel at least at the end of its movement through said given degree, to shift outwardly in spaced relation to said ratchet wheel, to swing backwardly, and to reengage the next adjacent tooth of said ratchet wheel.

10. A typewriter according to claim 9 in which said first cam has one surface extending in a general radial direction, another surface which is arcuate, and another surface, which might be termed a corner surface, joining said first and second mentioned surfaces, said first surface being adapted to engage said link and advance it in a direction to advance the ratchet wheel, said corner surface being adapted to cause said link to decelerate said wheel, and said second mentioned surface being adapted to hold said link out of engagement with said ratchet wheel.

11. In a typewriter, a frame, keys on said frame, a carriage movable on said frame, a reciprocating universal bar controlled by said keys, a unidirectional escapement mechanism operatively connected to said carriage and comprising a rotary dog having a plurality of teeth on the periphery thereof, a ratchet wheel secured to the axis of said dog and having twice as many teeth as said dog has, a propelling-unit pivoted on said frame and including a pivoted link carrying a stud which normally engages a space between two teeth on said ratchet wheel, and a driving-unit having a first cam to actuate said propelling-unit, and a second cam to actuate said link, said universal bar being adapted to oscillate said driving-unit, each full oscillation of said driving-unit causing said stud to make a round trip along a somewhat quadrilateral path, thereby advancing said ratchet wheel one step and engaging the next adjacent space on said ratchet wheel.

12. In a typewriter, a frame, keys on said frame, a carriage movable on said frame, a universal bar oscillated by the action of said keys, an escapement mechanism operatively connected to said carriage and including a toothed escapement wheel and a toothed rotary dog, both of which are mounted in said frame with their axes 90° apart, a ratchet wheel movable with said dog and having twice as many teeth as said dog has, and differential-pawl means comprising a propelling unit and a driving unit, both of which are pivotally mounted on said frame, said propelling unit having a toothed link pivoted thereon in operative contact with said ratchet wheel, said driving unit cooperating with said universal bar and having a first control thereon to actuate said toothed link and a second control thereon to actuate said propelling unit, said driving unit adapted to be oscillated by said universal bar and adapted in turn to oscillate said propelling unit along a path extending in a plurality of directions, thereby rotating said ratchet wheel through a given angle in a single direction.

13. In a device for transforming high frequency reciprocal strokes into stepped rotary

movement, a frame, a ratchet wheel rotatably mounted on said frame, a propelling unit pivoted on said frame and including a pivoted toothed-link oscillatable about both pivots and normally engaging a space between two teeth of said ratchet wheel, a driving-unit journalized on said frame and carrying at least two selectors each of which is adapted to drive said toothed-link about a different one of said pivots, and reciprocating means to oscillate said driving-unit, each oscillation of said driving-unit causing said selectors to sequentially oscillate said toothed-link about said pivots, thereby causing said toothed-link to rotate said ratchet wheel one step while advancing along a first path, to shift away from said ratchet wheel while moving along a second path, to decelerate the rotation of said ratchet wheel at least while disengaging therefrom, to return along a third path different from said first and second paths, and to reengage with the next predetermined space between teeth on said ratchet while moving along a fourth path differing from said first three paths, said link being entirely free of and spaced apart from said ratchet wheel between the time it is disengaged from and the time it is reengaged with said ratchet wheel.

14. The invention according to claim 13, in which said toothed-link is so arranged that the second and the fourth paths only are increased and decreased as the length of stroke of said reciprocating means is increased and decreased respectively.

15. In a device for transforming high frequency reciprocal strokes into stepped rotary movements, a frame, a ratchet wheel rotatably mounted on said frame, link means arranged to be oscillated about a plurality of spaced pivots and carrying a stud which normally engages a space between two teeth on said ratchet wheel, a member supported on one of said pivots and carrying said link means and the pivot supporting it, and an oscillatory driving-unit carrying a first cam to actuate said link means and a second cam to actuate said member and to thereby controllably drive said stud about said pivots, each oscillation of said driving-unit causing said stud to move in a sequence, wherein said stud first moves along a forward path, then veers along a second path, then moves backward along a third path, and finally veers along a fourth path towards its normal position and enters into the next and predetermined space between teeth of said ratchet wheel, thereby completing a somewhat quadrilateral path which results in the rotation of said ratchet wheel by said stud.

16. In a device for transforming high frequency reciprocal strokes into stepped rotary motion, a ratchet wheel, a free return pawl positioned to be motivated by said reciprocal strokes and adapted to engage and rotate said ratchet wheel, multiple supports for said pawl and dual cam means acting sequentially against said multiple supports for said pawl for causing the latter to sequentially reengage with successive teeth of said ratchet wheel in timed relation with the occurrences of said strokes regardless of the frequency of the same.

17. A free return pawl oscillatable about two spaced pivots, one of which is devised to enable said pawl to oscillate in one direction, and the other of which is devised to enable said pawl to move in a second direction, and driving means for effecting the oscillation and including cam means of one radius for controlling the move-

ment of said pawl in said first direction and a cam of a different radius for controlling the movement in said second direction.

18. In combination with a ratchet wheel, a pawl oscillatable about a plurality of spaced pivots, each of which enables said pawl to move along a series of paths in different and predetermined directions, which collectively comprise a somewhat quadrilateral path, a unit member supported by one of said pivots and carrying the other of said pivots, a pawl supporting member carried by the other of said pivots, and driving means having cam means acting against one of said members and a second cam means acting against the other of said members, the axis of said cam means coinciding with the axis of said ratchet wheel, and the axes of all said pivots lying outside the periphery of said ratchet wheel.

19. A toothed wheel, a toothed link to rotate said wheel unidirectionally in steps, and compound cam carrying means having an axis coinciding with the axis of said toothed wheel cooperating with said link to decelerate the rotation of said wheel at approximately the end of each of said steps.

20. A toothed wheel, a toothed link oscillatable about two spaced pivots and normally engaging a tooth on said wheel, cam means to drive said link about one of said pivots to cause said link to drive said wheel, and a second cam means to drive said link about the other of said pivots for causing said link to disengage said first tooth and engage another tooth on said wheel.

21. In a device for converting strokes of a reciprocal universal bar, the lengths of which may vary between a limited minimum and a limited maximum, to constant stepped rotary motion; a unit in cooperative relation with said universal bar and carrying at least two driving members, one of which has a constant time-space relationship with the beginning of the forward stroke of said universal bar, while the other one has a constant time-space relationship with a given fraction of said stroke, the extent of which is shorter than said minimum length; a second unit including at least two links, each of which is driven by said members in an ordered sequence so that a projected point of one of said links traces a planetary path in which it moves an increment A in one direction, an increment B in a different direction, an increment C in yet another direction, then an increment D in a direction somewhat opposite said different direction until it reaches its initial and normal position, thereby tracing a somewhat quadrilateral figure, the sides of which are formed by said increments A, B, C and D respectively, the extent of the elongation of the side A and the side C, being constant as the resultant of said predetermined portion of said minimum stroke, while the extent of the elongation of the side B and the side D is variable as the resultant of the remaining portion of the reciprocal stroke from said portion to the end thereof, and a toothed wheel having one tooth normally engaged by said projected point of said one link and adapted to be rotated a predetermined fraction of a revolution by the latter as it moves along a given portion of said path, irrespective of any variations in the length of said stroke.

22. In a device for converting variable strokes of a high frequency reciprocal universal bar to rotary motion, a ratchet wheel supported for rotation, a unit in cooperative relation with said universal bar and carrying at least two driving

members, and a second unit including at least two links each of which is driven by said members in a sequential order so that a projected point of one of said links, which normally engages said ratchet wheel, traces a planetary path in which it moves an increment A in one direction, an increment B in another direction, an increment C in a third direction, and an increment D in a direction different from said second direction, until it reaches its initial position in engagement with a different tooth of said ratchet wheel, thereby tracing a somewhat quadrilateral figure, the sides of which are formed by the increments A, B, C and D respectively, said sides A and B being produced during the forward stroke of said universal bar and consequently as fast as said universal bar makes its forward stroke, while said sides C and D are produced during the backward stroke of said universal bar under the urge of spring means as fast as said universal bar makes its return stroke, said ratchet wheel being rotated a fraction of a revolution while said projected point is passing along a predetermined increment of said quadrilateral path.

23. In a converting mechanism, a toothed wheel, a toothed link having a single shaft normally in mesh with at least one tooth of said wheel, a compound support for said link, a reciprocating universal bar, means actuated by the forward stroke of said universal bar including a first cam means to cause said link to first drive said wheel and a second cam means acting against said compound support for said link to disengage said link and move it away from said wheel, and a second means comprising spring power to return said link to its initial position in mesh with another tooth of said wheel.

24. In apparatus of the character described, a ratchet wheel, a double driven free return single pawl to propel said wheel, compound supports for said pawl, driving means carrying compound cams in cooperative relation with said supports, and reciprocally moved means actuating against said driving means to cause sequential movement of said driving means and the sequential action of said cams against said supports.

25. In a device for producing rotary motion in steps, a ratchet wheel, free return pawl means to propel said wheel, an intermediate member forming a support for said pawl means and two driving means to actuate said pawl means, one actuating it directly and the other actuating it through said intermediate member supporting said pawl means.

26. In a motion converting device, a rotary toothed wheel, an oscillatory toothed link in operative mesh with said wheel, a pivoted support for said link, driving means carrying dual cam means to directly drive said link and thereafter to drive it by moving said pivoted support, whereby said link is actuated at least twice in succession by said driving means to rotate said wheel a single step, said link being disengaged from one tooth of said wheel and re-engaged with a succeeding tooth the while.

27. In a motion converting device, a ratchet wheel, a pawl to rotate said wheel in steps, said pawl being oscillatable about at least two spaced pivotal centers, a unit member pivotally supported on one of said centers, a support for said pawl pivoted to said unit member on the other of said centers, and means including compound cam means to oscillate said pawl about said centers.

28. In an escapement mechanism, two toothed members normally in mesh, one of said members

being movable on a single pivot and having an outer periphery, the other of said members being movable on at least two spaced pivots the axes of which lie outside said periphery and adapted to swing once on each of its pivots while said first member swings once on its pivot, and a driving member carrying elements for effecting the swinging of said other member as aforesaid.

29. In a device for transforming reciprocal strokes of a universal bar into stepped rotary motion, a ratchet wheel, dual controls, a differential pawl motivated by said dual controls during each of the forward strokes of said universal bar to engage and rotate said ratchet wheel, and driving means cooperating with said controls and rendering said controls effective to cause the disengagement of said pawl from said ratchet wheel when said universal bar, during its forward stroke, travels a predetermined distance, so that further travel of said universal bar beyond said distance will not impart further movement to said ratchet wheel.

30. In an intermittent rotary mechanism, a rotatable driving toothed member, a rotatable driven toothed member, said first member normally having one tooth operatively engaging one tooth of said driven member, a fixed stop and guide member having a straight portion adjacent to and overlapping said driven member and normally contacted by said first tooth, and means to intermittently rotate said driven member by moving said driving member, to disengage the tooth of said driving member from said driven member, to move said driving member into engagement with said stop and guide member, and to re-engage said driving member with another tooth of said driven member, said driving member being free and out of contact with said driven member from the time it is disengaged until the time it is guided to and re-engaged with said driven member.

31. In an intermittent rotary mechanism, a rotatable driving toothed member, a rotatable driven toothed member, said first member normally having one tooth operatively engaging one tooth of said driven member, a fixed stop and guide member having a straight portion adjacent to and overlapping said driven member and normally contacted by said first tooth, and means to intermittently rotate said driven member by moving said driving member, to disengage the tooth of said driving member from said driven member, and to move said driving member into engagement with said stop and guide member, said driving member being free and out of contact with any portion of said mechanism from the time it is disengaged from said driven member until the time it comes in contact with said guide member, said guide member being adapted to change the direction of movement of said drive member and to guide it into re-engagement with another tooth of said driven member.

SEYED KHALIL.
